CLAIM

The ornamental design for a piston-type spackle dispenser, as shown and described.

DESCRIPTION

FIG. 1 is a front elevational view of a piston-type spackle dispenser showing my new design, the tip member removed for convenience of illustration;

FIG. 2 is a top plan view of FIG. 1;

FIG. 3 is a bottom plan view of FIG. 1;

FIG. 4 is a side elevational view of the tip member with the dispenser body removed for convenience of illustration;

FIG. 5 is a top plan view of FIG. 4;

FIG. 6 is a cross-sectional view of FIG. 5 taken in the direction of arrows 6—6;

FIG. 7 is a front elevational view of my design; and,

FIG. 8 is a front elevational view of FIG. 7 in an exploded condition.
